UNITED STATES PATENT OFFICE.

WILLIAM ANDERSON, OF HEBBURN-ON-TYNE, AND HENRY WILLIAM CLOTHIER, OF WALLSEND-ON-TYNE, ENGLAND, ASSIGNORS TO A. REYROLLE & COMPANY LIMITED, OF HEBBURN-ON-TYNE, ENGLAND, A COMPANY OF GREAT BRITAIN.

METAL-CLAD ELECTRIC SWITCH GEAR OF THE DRAW-OUT TYPE.

Application filed February 4, 1926, Serial No. 86,103, and in Great Britain April 2, 1925.

This invention relates to metal-clad electric switchgear of the draw-out type and more particularly to switchgear in which the sockets on the fixed portion of the gear are provided with doors or covers which are opened and closed automatically by the movement of the draw-out portion of the gear. These doors are hinged or pivoted and when the draw-out portion of the gear is racked in they are caused by the action of operating rods to fold together and slide into a space between two sockets for instance a busbar socket and a transformer socket, provision being made for a further racking in motion of the draw-out portion without further motion of the doors.

The objects of the present invention are an improved construction and arrangement of the operating gear for these doors or covers and the provision of means whereby the doors of the busbar sockets cannot be opened by hand when in the closed position into which they are moved by the withdrawal of the draw-out portion of the gear.

In switchgear according to the present invention one or more of the doors is provided with gear or otherwise operatively connected to the operating rod so that when the door is opened by the racking in of the movable portion of the gear, the turning of the door about its hinge or pivot frees the operating rod from its positive engagement with the draw-out portion and allows that portion to continue its racking in motion.

This operative connection between the door and the operating rod is conveniently made by means of bevel gear, a bevel pinion mounted on the hinge or pivot of the door engaging with another bevel pinion on the operating rod. The operating rod has its ends supported in sleeves or guides on the fixed and draw-out portions respectively, the sleeve or guide on the draw-out portion having a longitudinal slot with a transverse notch or recess in it and the adjacent end of the operating rod being furnished with a pin or grub screw which by rotation of the rod can be brought out of the longitudinal slot into the transverse recess or vice versa. It is this partial rotation of the rod which is effected by the opening and closing of the door through the bevel or other gear above mentioned.

In switchgear of the type to which this in-

vention relates it is sometimes necessary to earth the transformer socket this generally being the lower socket of the two or more sockets on the gear. To do this an extension plug is placed in the corresponding socket of the draw-out portion and after the door or cover of the transformer socket has been opened the draw-out portion is racked in sufficiently to bring the plug into engagement with the socket, appropriate earthing connections having been made on the draw-out portion. It is very desirable that when carrying out this operation which necessitates the opening of the transformer socket door by hand, that there should be no risk of the busbar chamber socket door being opened by mistake. To obviate this risk according to this invention the door of the busbar chamber is so arranged that whilst it can be opened and closed through the action of the operating rod in the normal use of the gear, it cannot be opened by hand from its closed position. This arrangement conveniently takes the form of a curved catch cooperating with a slot in the door and so shaped that it allows the door to open when its hinge or pivot is being shifted by the movement of the operating rod but prevents the turning of the door about its hinge or pivot when that member is stationary.

In multi-phase switchgear the doors of neighbouring phase sockets are usually connected by a web or plate and this web can be slotted to allow a fixed curved plate catch to pass through it, the dimensions of the slot and the curve of the catch being such as to fulfil the conditions above mentioned.

When the invention is applied to switchgear having duplicate busbar sockets one above the other, each of the busbar socket doors is furnished with a catch or other locking arrangement acting in the manner described and in such a case the operating rod for the upper busbar socket merely slides in guides on the fixed and draw-out portions respectively and is connected by a tie to the operating rod for the doors of the lower busbar chamber and the transformer chamber. This lower rod, as previously mentioned, is provided with pins and the slotted and notched guide and is geared through the bevel pinions to the door of the transformer socket.

The sleeves or guides on the draw-out por-

tion are preferably attached to that portion in such a way that they can be easily removed when necessary when the switch is in the withdrawn position and the doors closed, but when the draw-out portion is racked in and the doors open, the arrangements are such that the sleeves or guides can only be removed by the use of a spanner or some tool. The withdrawal of the draw-out portion without closing the doors is thus prevented unless that operation is preceded by some deliberate action.

15 Springs may be provided to counteract any tendency of the pins or grub screws from sticking in the longitudinal slots in the guides.

20 In the accompanying drawings which illustrate by way of example one construction of the invention as applied to draw-out switchgear for duplex busbars,

25 Figure 1 is a side elevation with a detail in section showing the draw-out portion in its withdrawn position and the doors closed,

Figure 2 is a section on the line 2—2 of Figure 1 showing the closed doors in elevation,

30 Figure 3 is a view drawn to a larger scale of a portion of Figure 2 with a part in section,

35 Figure 4 is a part section on the line 4—4 of Figure 2 drawn to the same scale as Figure 3 but showing the doors A³ B⁴ in the act of being opened,

Figure 5 is a view similar to Figure 1 40 but showing the draw-out portion racked in and the doors open,

Figure 6 is a view similar to Figure 1 but showing the door of the transformer chamber open, and

45 Figures 7 and 8 are detail views of the guide tubes on the draw-out portion of the gear to show the interconnection between the rods, the tubes and the retaining studs, Figure 7 showing the positions of the parts when the draw-out portion is racked out and Figure 8 the positions when it is racked in.

Like letters indicate like parts throughout the drawings.

50 In these drawings A and A¹ are the bus-bar sockets or chambers and B the transformer socket or chamber, all forming part of the fixed portion of the gear. C and C¹ are the plugs for the busbar sockets A and A¹ respectively and D is the plug for the transformer socket B, these plugs all being carried on the draw-out portion of the gear. The switchgear shown is designed for use on a three-phase system so that there are three sets of plug and socket connections arranged side by side in the usual manner.

55 All the chambers or sockets are provided with doors marked A², A³ and B¹ respectively and the doors in each horizontal row are connected by webs as may be seen by reference to Figure 2.

The operation of opening and closing the doors is brought about by the backward and forward movement of rods E and E¹ mounted in guides F on the fixed portion and guide tubes G and G¹ on the draw-out portion.

70 The lowest or transformer chamber door B¹ on each side is secured, say by a pin, to a tube H (Figure 3) which can turn about a rod H¹ and carries a bevel pinion H² pinned to the tube and engaging with a similar pinion H³ on the rod E which passes through and can rotate in an eye H⁴ on the rod H¹. On each side of this eye H⁴ is a collar E² pinned to the rod E.

75 The lower busbar chamber door A³ is 80 hinged about the tube H, that is to say it can turn on the tube and is not pinned to it. The upper busbar chamber door A² at each side of the gear is similarly hinged about a rod H⁵ carried between collars E³ on the rod E¹. Springs J are provided which tend to keep all the doors closed over the mouths of their respective chambers.

85 The end of the rod E remote from the fixed portion of the gear slides in the guide tube G which is formed with a longitudinal slot G² and a transverse slot or notch G³. It is also formed with a second transverse slot or notch G⁴ whose function is described later.

90 When the draw-out portion is in the racked out position, i. e. that shown in Figure 1, a pin or grub screw E⁴ on the rod E is in engagement with the transverse slot G³ and therefore, if the draw-out portion be 95 racked in, the rods E will be pushed forward and by means of the collars E² will carry the rods or pivot pins H¹ backwards thus causing the doors A³ and B¹ to open, as shown in full lines in Figure 4, against the action of the springs J. The rods E¹ are merely guided by their tubes G¹ which are not provided with the slot and notches of the tubes G, but the rods E¹ are tied to the rods E by the brackets or ties E⁵ so that the rods E¹ also move with the rods E and the upper doors A² are also carried back and opened.

100 As the transformer chamber door B¹ is 115 opened the tube H to which it is pinned is partially rotated and consequently the bevel pinion H² turns and through the pinion H³ rotates the rod E. This causes the grub screw or pin E⁴ to move in the transverse slot G³ until it is finally brought out of that slot into the longitudinal slot G². By this time the doors are fully open and are folded and stowed between the chambers as indicated in Figure 5. Further racking in movement of the draw-out portion to complete the plug and socket connections is now possible without moving the rods E, for the tubes G now slide forward on the rods. The pin E⁴ being in the longitudinal slot G² 120 permits of this movement. This final closed 125

position of the gear is shown in Figure 5.

The reverse operation takes place when racking out the draw-out portion, the guide tubes G first sliding over the rods E and 5 consequently not moving the doors until the grub screws or pins E⁴ are at the inner end of the longitudinal slots G² and adjacent to the transverse notches G³. Further outward 10 movement pulls the rods E and E¹ and 15 brings the rods or pivot pins H¹ and H⁵ forward so that the doors may turn under the action of their springs into their closed positions. In thus moving the lower door B¹ operates the bevel gear and the rod E is rotated, this movement being allowed by the 20 transverse slot or notch G³.

When, as is sometimes necessary, the lower or transformer socket B has to be earthed through the racking in of the draw-out portion 25 after some part of that has been connected to earth, this can be done by opening the door B¹ by hand and holding it open as for example by a link as at K in Figure 6. This movement of the door B¹ turns the rods 30 E¹ and brings the grub screws or pins E⁴ out of the transverse notches G³ into the longitudinal slots G². The draw-out portion can then be racked in without operating the doors and if an extension plug or earthing contact such as L be placed on the plug 35 D, this racking in motion will suffice to earth the socket B whilst the busbar chamber doors A² and A³ remain closed.

Whilst it is desirable thus to be able to 40 open the transformer chamber doors B¹ by hand, it is important that there should be no risk of one of the busbar chamber doors A² and A³ being opened by mistake and therefore provision is made to prevent this.

In the construction illustrated the webs 45 joining the busbar chamber doors are provided with slots M which in the normal opening and closing movements of those doors pass freely over fixed curved catches N. The shape of these catches is such that they only allow the slots M to pass over them when the centres, i. e. the rods H¹ and H⁵ about which the doors A² and A³ turn, are being moved by the normal operation of the 50 switchgear, i. e. by the racking in or out of the draw-out portion. If it be attempted to open the doors A² or A³ by hand, i. e. to turn them about the rods H¹ and H⁵ when those members are stationary, the catches N 55 will foul the slots M and prevent the doors from being opened. This can be seen by reference to Figure 4 where one of the doors A³ is shown in chain lines in its closed position. If it be turned about its pivot rod H¹ 60 when in this position the edge of the slot M will obviously foul the fixed catch N whereas if the pivot rod H¹ is being moved by the rod E in the normal operation of the gear the arc described by the slot M corresponds 65 to the curve of the catch N.

It may occasionally be desired to free the draw-out portion from mechanical connection with the fixed portion, i. e. to break the operative connection formed between these portions by the tubes G and G¹ and the rods E and E¹. Whilst it is desirable that this may be done quickly and easily when the draw-out portion is withdrawn and the doors closed, it should be impossible to do it otherwise than with deliberate intent when 70 the doors are open. For these reasons the tubes G are made with the second transverse notch G⁴ previously mentioned and are secured in their supports on the draw-out portion of the gear in the way now to be described with reference to Figure 1 and to Figures 7 and 8. As will be seen by reference to Figure 1 the tube G is secured to its support G⁵ by two set screws. One of these O has a milled head and thus can be readily 75 and quickly removed. The other P has a head which necessitates the use of a spanner or tool and cannot be undone by hand. The stud O grips the tube G whilst the stud P does not grip it but normally enters the 80 second transverse slot G⁴ and prevents any longitudinal motion of the tube relative to its support G⁵. When the draw-out portion has been withdrawn and the doors are 85 closed, the parts occupy the position shown in Figure 1 and Figure 7, i. e. the pin E⁴ is 90 in the transverse slot G³ in a position corresponding to that of the stud P in the other transverse slot G⁴. Thus by loosening the 95 one stud O the tube G can be turned in its support in the direction of the arrow (Figure 7) which will bring the longitudinal slot into line with the pin E⁴ and the stud P, i. e. will disengage those members from 100 their transverse slots. The tube G can then 105 be slid over the rod and freed from its support G⁵.

But when the doors are open, i. e. when the draw-out portion has been racked in, the 110 position of the parts will be as indicated in Figure 8 and then the mere loosening of the stud O will not be sufficient, for as the pin E⁴ is now in the longitudinal slot G² the tube cannot be turned relatively to its support to bring the second transverse slot 115 out of engagement with the stud P, neither can the tube slide longitudinally because of the presence of the stud P in its transverse slot. Consequently the stud P must be removed by a tool or spanner before the tube 120 can be removed from its engagement with the draw-out portion. The two studs O and P are shown opposite to each other in Figure 1 but in Figures 7 and 8 the position of the stud P is slightly altered to make the 125 above described action clearer. As previously mentioned the tubes G¹ for the upper rods E¹ are only guide tubes and they are therefore merely held by studs O¹ functioning similarly to the studs O.

The spring R shown in Figure 1 is not essential to the invention, one end if it is attached to the fixed portion of the gear and the other say to the pivot rod H¹ or to the 5 collar of the bevel pinion H². Its function is merely to prevent the pin E⁴ tending to stick by friction in the slot G². There are preferably two such springs, one on each side of the gear.

10 It will be understood that in switchgear according to this invention not intended for a duplex busbar system, the upper busbar chambers A and doors A² would not be present and the rods E¹ and ties E⁵ would be 15 omitted.

What we claim as our invention and desire to secure by Letters Patent is:—

1. In electric switchgear of the draw-out type having sockets on the fixed portion provided with doors which are opened and closed by the reciprocation of operating rods attached to the draw-out portion, the combination with one of said doors of gear between it and its operating rod, such gear 20 being actuated by the door itself when it is opened to free the operating rod from positive engagement with the draw-out portion.

2. In electric switchgear of the draw-out type the combination of a fixed portion, socket chambers forming part of said fixed portion, hinged doors to said chambers, a draw-out portion, an operating rod having one end held in a tubular support on said draw-out portion and its other end slidably mounted on said fixed portion, and bevel gear between one of said doors and said operating rod acting to turn the rod and free it from its positive engagement with its tubular support on the draw-out portion when said door 35 is opened.

3. In electric switchgear of the draw-out type the combination of a fixed portion, a busbar socket chamber and a transformer

socket chamber forming part of said fixed portion, hinged doors to said chambers, a 45 draw-out portion, an operating rod having one end held in a tubular support on said draw-out portion and its other end slidably mounted on said fixed portion, bevel gear between said transformer chamber door 50 and said operating rod acting to turn the rod and free it from its positive engagement with its tubular support on the draw-out portion when said door is opened, and means for automatically locking the busbar 55 chamber door so that it cannot be opened by hand when in the closed position into which it is moved by the withdrawal of the draw-out portion of the gear.

4. In electric switchgear having the combination of parts set forth in claim 3 the combination with the busbar chamber door of a curved catch so shaped as to allow a slot to pass over it when the door opens under the action of the operating rod but to 60 prevent the opening of said door by hand when said rod is inoperative.

5. Electric switchgear having the combination of parts set forth in claim 2 in which the operating rod is provided with a pin and 70 is engaged with the draw-out portion by a tube having longitudinal and transverse slots to accommodate said pin, said tube being removably held in a support on the draw-out portion in such a manner that 75 whilst it can be readily detached therefrom when the draw-out portion is racked out and the doors closed, such detachment can only be effected when the draw-out portion is racked in and the doors open, by the deliberate manipulation of two fastening members. 80

In testimony whereof we have signed our names to this specification.

WILLIAM ANDERSON.
HENRY WILLIAM CLOTHIER.
